**COVER UNIT FOR PARTICULATE MATERIAL
SPREADER AND THE LIKE**

Loren E. Tyler, 102 Chevy Chase Drive,
Wayzata, Minn. 55391

Filed Sept. 2, 1969, Ser. No. 18,933

Term of patent 14 years

Int. Cl. D15—03

U.S. Cl. D35—2

FIG. 1

FIG. 2

FIG. 3

FIG. 4

FIG. 5

FIG. 1 is a top plan view of the cover unit for particulate material spreader and the like of the invention in the closed position;

FIG. 2 is a plan view similar to FIG. 1 showing the cover unit in the open position;

FIG. 3 is an enlarged sectional view taken along the line 3—3 of FIG. 1;

FIG. 4 is a side elevational view of the closed cover unit; and

FIG. 5 is an end elevational view of one hinged end of the cover unit. The other hinged end of the cover unit is identical in structure and appearance.

I claim:

The ornamental design for cover unit for particulate material spreader and the like, substantially as shown and described.
